UNITED STATES PATENT OFFICE.

JOHN E. LEONARD, OF PORTLAND, OREGON.

MOVING-PICTURE MACHINE.

1,102,988.

Specification of Letters Patent.

Patented July 7, 1914.

Application filed March 28, 1912. Serial No. 686,908.

To all whom it may concern:

Be it known that I, JOHN E. LEONARD, a citizen of the United States, residing at Portland, in the county of Multnomah and 5 State of Oregon, have invented certain new and useful Improvements in Moving-Picture Machines, of which the following is a specification, reference being had therein to the accompanying drawing.

10 My invention relates to improvements in moving picture machines.

The object of my invention is to provide means for feeding the film across the lens and to dispense with the usual perforations 15 necessary in the edge of the film, although films having these perforations can be readily used upon my machine.

Another object of my invention is to provide means whereby the film can be started 20 from the reel and will be guided directly of its own accord to the feeding mechanism and then guided to the reel upon which it is wound.

A still further object of my invention is 25 to provide a more simple, cheap and effective means for feeding the film across the lens and intermittently stopping and starting the same for exposing the picture.

In the accompanying drawing—Figure 1 is 30 a side elevation of my improved moving picture machine showing the internal drive gear removed. Fig. 2 is a side elevation showing the hinged side swung outwardly exposing the film feeding mechanism. Fig. 3 is a vertical longitudinal sectional view of Fig. 2, showing the feeding mechanism on its upward movement to again engage the film. Fig. 4 is a vertical sectional view similar to Fig. 3, showing the film gripped by the feeding mechanism on its downward movement. Fig. 5 is an enlarged sectional view of the 35 winding spool showing the manner of attaching the film thereto. Fig. 6 is an enlarged plan view of the film engaging member 18.

Referring now to the drawings, 1 represents a rectangular casing having at its forward edge an opening 2, opposite the lens 3, and said opening is closed by a slide 3', 40 all of which is of the ordinary structure of a moving picture machine. One side of the casing is hinged at 4 whereby access to the interior mechanism of the machine may be readily had. The rear edge of the casing 45 is provided with a hinged door 5, for the entrance of light from the lamp when pro-

jecting only, as well understood by those skilled in the art. The upper edge of the casing 1 is provided with a hinged cover 6, whereby the film carrying case 7 may be 60 readily removed or inserted for replacing new films or removing old ones from the machine.

The case 1, at its forward end, as heretofore stated, is provided with a lens 3 opposite the opening 2, although the lens could be applied on the outside of the machine. The lens as shown is permanently supported between the sides of the casing, and surrounding the lens is a rotary shutter 8, 70 having at its outer end a gear 9 on the outside of the hinged cover 4, whereby the shutter is rotated around the lens. The specific construction and arrangement of this lens is fully described in a co-pending 75 application filed March 3rd, 1911, Ser. No. 612,126 and needs no further detailed description.

Below the shutter is mounted a transverse shaft 10 having an eccentric 10' arranged 80 thereon and surrounding said eccentric is a band 11 carried by the arm 12 pivoted at 12' and secured to said arm is a pitman 13. The outer end of the shaft 10 extends through the hinged cover 4 of the casing and 85 is provided with a gear 14 by means of which the shaft 10 is rotated, all of which will be hereinafter more fully described.

The casing 1 is provided with a vertical divisional plate 14', having an opening 15 90 therein opposite the lens. Carried by the divisional plate 14' is a plate 16 to which is rigidly secured a spring arm 17, having at its lower end a soft enlarged film engaging portion 18, which is adapted to engage the 95 film and press it against the divisional plate 14' and hold the film stationary while the shutter is open. The spring arm 17 normally holds this soft enlarged portion 18 against the film. The pitman 13 has its outer end 100 pivotally connected at 19 to the member 18 carried by the spring arm 17, whereby the film is intermittently gripped and held stationary while the shutter is open.

The divisional plate 14' has guide-ways 105 20, in which the vertically movable film carrying member 21 vertically slides. The upper end of said film guide 21 is provided with an outwardly extending arm 22, to which is pivotally connected at 23, the pitman 24, which extends downwardly and is connected to a wrist-pin 25, carried by the

disk 26. The said disk 26 is rigidly secured to the shaft 27, which extends outwardly through the hinged side 4 of the casing and carries on the outer side thereof a gear 28, by means of which the said shaft is rotated. The rotation of the shaft 27, as will be seen, will cause the film carrying guide 21, to reciprocate in the guide 22, as heretofore stated.

10 The film guide 21 is provided with an opening 29, through which passes a film engaging member 30, carried by the pitman 24. This film engaging member 30 is made of soft material so as not to disfigure the film, yet frictionally engaging the film so as to cause it to be moved thereby. In Fig. 3 of the drawing the film carrying guide 21 is traveling upwardly. After the wrist pin 25 has passed the center the pitman again travels downwardly. At the same time the film engaging member 30 passes through the opening 29 in the film guide and firmly clamps the film against the rear wall thereof, the continued downward movement of the pitman draws the film the desired distance to expose another picture. The pitman 24, as clearly shown is of a broad form and has an elongated opening 24' of sufficient length to at all times expose that portion of the film opposite the opening 15 in the divisional plate 14', whereby the reciprocation of the pitman will in no way interfere with the exposure of the picture. The reel carrying frame or box 7 is of the usual form having a reel 31 at its upper end, and a reel 32 at its lower end. The film-carrying member 7 adjacent the reel 31 is provided with an opening 33 and on the outside of the frame 7 a roll 34 is provided over which the film 40 is adapted to pass.

The casing 1 is provided with a roller 35, driven by a gear 36 on the outside of the cover 4. The film passes between the rollers 34 and 35 and is fed outwardly to the groove plate 37, which leads downwardly within the flared upper end 21' of the film carrying guide 21.

Below the lower end of the film carrying guide 21 the casing is provided with a grooved plate 28' which leads upwardly to an opening 39 in the film carrying frame 7 opposite the reel 32. The film 40, as clearly shown in Fig. 3 of the drawings, travels outwardly through the opening 33 between the rollers 34 and 35 and follows the curvature of the plate 37 entering the upper flared end of the film guide 21 and passes downwardly through the same. As the film leaves the guide 21, it engages the curved plate 28' and is guided through the opening 39 into the reel carrying frame 7 and is wound upon the spool 32.

It will be seen from the drawing that the spool 31 is not driven, but that the feeding guide 21 unwinds the film therefrom. The

shaft 41 of the spool 32 extends outwardly through an opening in the hinged cover 4 and is provided with a friction disk 43 which engages the outer periphery of the internal gear 44.

The hinged cover 4, of the casing is provided with a stud 46, upon which is mounted the internal gear 44. The gear 44 is provided with a handle by means of which it is readily rotated. In Fig. 1 of the drawings 75 it will be readily seen that the gears 36, 9, 28 and 14 are so located that they engage the internal gear 44 and the rotation thereof causes each and all of said gears to rotate at the proper speed.

From the foregoing description it will be seen that the film is at all times within the film guide 21 and the arm 12 and the pitmen 13 and 24 are so arranged in respect to each other that the film gripping member 18 is holding the film tightly against the divisional plate when the film carrying member is traveling upwardly. When the film is thus gripped the shutter of the lens is opened to expose the film. As the shutter closes, the pitman 24 has reached its upward stroke and the film engaging member 30 passes through the opening 29 and grips the film against the rear wall of the guide 21 and a continued downward movement of the pitman draws the film downwardly at a distance equal to another picture. As the film starts on its downward movement the pitman 13 has forced the member 18 outwardly to release the film and allow it to be drawn or wound upon the roll 32. This operation takes place as long as the internal gear 44 is rotated. The movement of the shutter 8 and the movement of the pitmen 13 and 24 are so timed that when the shutter is opened 100 exposing the film the gripping member 18 is holding the film against the partition 14 and the guide 21 is traveling upwardly to again grip the film and feed it downwardly for another picture.

The film engaging and gripping member 18 is provided with a central cutaway portion 18' leaving at each end the film engaging flanges 19' and 20' which engage the edge of the film beyond the picture and thus prevent any scratching or marring of the picture on the film.

Having thus described my invention, what I claim and desire to secure by Letters Patent is:

1. A moving picture machine comprising a lens, a film exposed to said lens, a shutter between the lens and film, a reciprocating member through which the film passes, a pitman for reciprocating said member and a film engaging member means for reciprocating the pitman carried by the pitman for clamping the film in the reciprocating member on its downward movement.

2. A moving picture machine comprising 130

- 5 a lens, a film exposed to said lens; a shutter between the lens and film, a reciprocating member through which the film passes and having an elongated opening exposing the film, a pitman connected to the upper end of the reciprocating member and having an elongated opening to correspond to that of the said member, and a film engaging member carried by the pitman for engaging the film and locking it to the reciprocating member on its downward movement.
- 10 3. A moving picture machine comprising a lens, a film exposed to the lens, a shutter between the lens and the film, a reciprocating member, a pitman for reciprocating the member, means carried by the pitman for clamping the film to the reciprocating member on its downward movement, and means for operating said pitman.
- 15 4. A moving picture machine, comprising a reciprocating member having a film exposing opening therein, a pitman for reciprocating the said member, and means carried by the pitman for frictionally holding the film against the member on its downward movement.
- 20 5. A moving picture machine comprising a reciprocating member having a film exposing opening, a pitman connected to the upper end of the reciprocating member and having an opening corresponding to the said opening in the reciprocating member, means for imparting a reciprocating and oscillating movement to the pitman, and means carried by the pitman for engaging the film and frictionally holding it to the reciprocating member on its downward movement.
- 25 6. A moving picture machine, comprising a reciprocating member having a film exposing opening, a pitman connected to the upper end of the said member and extending downwardly and having an opening corresponding to the opening in the reciprocating member, means for imparting a reciprocating and oscillating movement to the pitman, and means carried by the pitman for frictionally holding the film against the reciprocating member on its downward movement.
- 30 7. A moving picture machine comprising a casing, a lens therein, a film exposed to the lens, a shutter intermediate the lens and the film, a reciprocating feeding guide for the film, and a pitman timed with the shutter, whereby the film is fed forward during the closed position of the shutter.
- 35 8. A moving picture machine comprising a lens, a film exposed to the lens, a shutter between the lens and the film, a reciprocating film guide through which the film passes, a pitman for reciprocating said guide and means carried by the pitman for gripping the film in the guide during the forward movement thereof.
- 40 9. A moving picture machine comprising a lens, a film exposed to the lens, a shutter intermediate the film and the lens, a film guide through which the film passes, a pitman for reciprocating the guide, means carried by the pitman for gripping the film in the guide during one movement thereof, and means for gripping the film during the other movement of the guide to prevent the backward feed of the film.
- 45 10. A moving picture machine comprising a frame, a reciprocating member in said frame and having a film opening, a pitman connected to the upper end of the reciprocating member and extending downwardly and having a film exposing opening corresponding to the film opening in the reciprocating member, a wrist pin connected to the lower end of the pitman, whereby a reciprocating and oscillating movement is imparted to the pitman, means carried by the upper end of the pitman for engaging the film and frictionally locking it against movement on the plate, an arm pivoted to the frame adjacent the lower end of the reciprocating member, an eccentric for reciprocating the arm, legs pivotally connected to the arm and having a soft film engaging member adapted to engage the film and timed with the pitman to lock the film against movement on the upward movement of the reciprocating member, substantially as shown and described.
- 50 11. A moving picture machine comprising a lens, a film exposed to the lens, a shutter intermediate the lens and the film, a reciprocating feed guide through which the film passes, a pitman timed with the lens and connected with the film guide, means carried by the pitman for gripping the film in the guide and moving it forward during one movement of the pitman, and means timed with the feed guide and the lens to grip the film and hold it during the exposure of the picture and the return of the feed guide.
- 55 12. A moving picture machine comprising a lens, a film exposed to the lens, a shutter intermediate the lens and the film, a reciprocating film guide through which the film passes, means for reciprocating the guide, means carried by the said reciprocating means for gripping the film in the guide during one movement thereof, and means timed with the shutter and the guide for gripping the film when the shutter is open and the feed guide is returning to its normal feeding position.
- 60 13. A moving picture machine, comprising a lens, two reels within the machine, a film exposed to the lens and wound upon one reel within the casing and winding upon the second reel in the casing, a shutter intermediate the film and the lens, the reciprocating feed guide passing across the lens and having openings opposite the lens
- 65 75 80 85 90 95 100 105 110 115 120 125 130

to expose the film, a pitman connected to the upper end of the guide, a member carried by the pitman and extending into the guide and gripping the film against the wall 5 thereof on the downward movement thereof, means for driving the pitman and timed with the lens and means timed with the feed guide and the lens for gripping the film and holding it when the shutter is 10 open and the feed guide is returning to its normal feed position to prevent the backward feed of the film.

14. A moving picture machine comprising a reciprocating member having a film 15 exposing opening, a pitman connected to the reciprocating member, means carried by the pitman for frictionally locking the film against the reciprocating member on its downward movement and means for locking 20 the film against movement on the upward movement of the reciprocating member.

15. A moving picture machine, comprising a reciprocating member having an exposing opening therein, a pitman connected to the 25 said reciprocating member, a film engaging member carried by the pitman, means for imparting a reciprocating and oscillating movement to the pitman whereby the film is locked to the reciprocating member on

the downward movement thereof, and 35 means for frictionally engaging the film and locking it against movement on the upward movement of the reciprocating member.

16. A moving picture machine, comprising a reciprocating member having a film 35 exposing opening, a pitman connected to the upper end of the reciprocating member and having a film exposing opening corresponding to the opening in the reciprocating member, a rotatable disk adjacent the lower 40 end of the pitman, a wrist-pin carried by the disk and to which is connected the pitman, means carried by the pitman for frictionally locking the film to the reciprocating member on its downward movement, an arm pivoted adjacent the lower end of the pitman, an eccentric operating the said arm, and means carried by the arm for engaging the film and frictionally holding it against movement on the upward movement of the 50 reciprocating member.

In testimony whereof I hereunto affix my signature in the presence of two witnesses.

JOHN E. LEONARD.
